VERTICAL DROP-OUT FUSE

William O. Schultz, South Milwaukee, Wis., assignor to Line Material Company, South Milwaukee, Wis., a corporation of Delaware

Application May 19, 1937, Serial No. 143,474

26 Claims. (Cl. 200—114)

This invention relates to drop-out type fuses for mounting on transformer terminal bushings.

In certain types of transformers comprising a transformer winding and a metal casing enclosing the winding, a primary lead-in terminal extends through the top of the casing and is provided with a bushing insulating the terminal from the casing. It is an object of this invention to provide a drop-out fuse structure adapted for 5 mounting on such a transformer terminal, the fuse structure including a fuse cartridge pivotally and slidably mounted on the terminal and automatically movable from circuit-closing position upon blowing of the cartridge.

More specifically it is an object to provide a drop-out fuse mounted on and above a transformer bushing for movement from circuit-closing to 10 open-circuit positions in a path extending vertically at an angle and beyond the top of the transformer casing and having its path of expulsion disposed at an acute angle relative to a vertical plane and extending beyond the outlines of the transformer, thereby to direct metallic vapors 15 expelled from the fuse away from the transformer.

Other objects are to provide a drop-out fuse which will produce a minimum torsional stress upon the transformer bushing and lead-in terminal when the fuse cartridge reaches its open-circuit 20 position after the fuse has blown, which is spring biased for sliding movement to open-circuit position, and in which a simple resilient flip-out spring strip having an integral tube-engaging portion is normally disposed in the path of movement of the tube, thereby reducing the stress upon 25 the fuse link to a minimum and extending the gap in the circuit before the tube moves.

Also it is an object to provide means interacting between the fuse tube and its pivot and sliding support for absorbing the reactive forces upon 30 the tube when the fuse link is ruptured.

Still another object is to provide for a pivotally and slidably mounted drop-out fuse a manipulating ring at its free end, aligning means for 35 assuring correct relative rotative relationship between the ring and the fuse pivot when the fuse is operative for movement to and is positioned in circuit-closing position.

In connection with the foregoing last-noted 40 object, it is also an object to provide for a drop-out fuse having a fuse link-controlled flip-out spring, means for retaining the fuse link against displacement relative to the spring.

Other advantages will become apparent as the 45 device disclosed herein is described.

In the drawings:

Fig. 1 is a view in side elevation, partly in section, showing the fuse in circuit-closing position.

Fig. 2 is a fragmentary view in side elevation showing the fuse in full lines in a horizontal position, and in broken lines in a position which it assumes after the fuse has blown.

Fig. 3 is a sectional view taken on the line 3—3 of Fig. 1.

Fig. 4 is a fragmentary view in side elevation 10 on reduced scale illustrating a position in which the fuse may be supported when the fuse link is operative for closing a circuit.

Like parts are identified by the same reference characters throughout the several views.

The transformer casing 1, shown fragmentarily, is provided with an insulation bushing 2 surrounding a lead-in conductor extending into the casing and having a flanged terminal member 3 at the 15 upper end of the bushing 2.

Mounted upon and secured to the member 3 by means of a stud bolt 4 is a current conducting support 5 having an inclined base plate 6 and a horizontally extending portion terminating in an inclined mounting plate 7 and relatively spaced 20 hooked pivot arms 8 extending downwardly and outwardly from the arm. Secured to the plate 7 by a suitable means, such as screw bolt 9, is a U-shaped contact 10 comprising two adjacent 25 strips of flat spring bronze.

An insulator block 11 is mounted upon the base plate 6 by means of a bolt 12 and extends upwardly therefrom at an angle normal to the plate. Secured to the upper end of the block 11 and insulated thereby from the arms 8, is a spring 35 contact plate 13 bent at 14 to provide a lead wire connecting portion and reversely curved at its floating end to provide a contact portion 15, a retainer portion 16 and a plate-actuating portion 17. As shown, the plate 13 is reinforced by a 40 spring strip 18, each of which is secured to the block 11 by means of the bolt 19.

The fuse cartridge comprises an insulating tube 20 having at its upper end a metal ferrule 21 provided with a radial flange 22, a pull ring 23 and a metal closure cap 24. The lower end of the tube is provided with a sleeve 25 slidable thereon and having the major portion of its bore enlarged to provide space for the coil spring 26 which is disposed about the tube and within the bore of the 45 sleeve 25. A collar 27 normally holds the spring 26 under compression.

A flip-out spring strip 29 is secured to the sleeve 25 by means of the threaded stud 30 and knurled nut 31 and is bent at its lower end to 50

provide a hook portion 32 extending beneath the collar 27. The fuse link 33 is electrically connected with the cap 24 by means of its terminal head 33' and extends from the open end of the tube about the hook portion 32 and upwardly along the strip 29 to the stud 30 where it is anchored by means of the nut 31.

The fact that the hook portion 32 is made arcuate as shown insures that no destructive abrasive action will be produced thereby upon the easily damaged fine wires of the fuse link when the latter is being connected to the sleeve 25.

The sleeve 25 is provided at its lower end with trunnions 35 receivable in the hooked portions of the pivot arms 8 and pivotally supporting the sleeve and tube upon the support 5. It will also be noted that the sleeve 25 is provided with lugs 36 positioned above and spaced from the trunnions 35. These lugs 36 serve as stops engageable with the lower margin of the U-shaped contact 10 when the reactive expulsion forces upon the tube 20 urge the tube upwardly, thereby preventing disengagement of the trunnions 35 from the hooked arms 8.

In circuit-closing position, illustrated in Fig. 1, the tube 20 extends angularly upwardly and from the axis of the trunnions 35 and towards the vertical axis of the bushing 2. In this position, the sleeve 25 is positioned within and in electrical contact with the U-shaped contact 10, and the cap 24 is in electrical contact with the curved portion 15 of the floating end of the contact spring plate 13. The axis of the tube 20 preferably lies in a vertical plane coinciding substantially with the plane of the axis of the bushing 2. Thus, when the tube 20 is moved into circuit-closing position, the closing force will be in a direction laterally toward the axis of the bushing 2.

If the fuse link 33 is ruptured under abnormal conditions, the resilient flip-out strip 29 will immediately widen the gap at the ruptured portion and initiate withdrawal movement of the link from the tube 20. While the link is being withdrawn from the tube, the curved portion 32 of the strip 29 will be moved from beneath the collar 27, thereby to release the tube for sliding motion through the sleeve 25 under the influence of the spring 26. When the tube has been released as noted, the coil spring 26 will move the tube downwardly at an angle extending beyond the casing 1 and will separate the cap 24 from the spring strip or plate 13.

In view of the fact that the tube 20 is disposed at a relatively sharp angle extending downwardly, it will continue its sliding motion through the sleeve until the flange 22 on the ferrule 21 contacts the plate 37. The plate 37 is secured to the sleeve 25 by means of the screw bolt 34 and is engageable with a tool (not shown) for removal of the cartridge from the arm 5. Since the sleeve is in frictional engagement with the U-shaped contact 10, the tube will be maintained in substantially the position shown in broken lines in Fig. 2.

The fuse may be moved from the position indicated by the broken lines in Fig. 2 by engaging an operating tool (not shown) with the pull ring 23, and rotating the tube in a clockwise direction about the axis of trunnions 35 until it extends in the horizontal position shown in Fig. 2. In this position, the collar 27 engages the bottom of the support 5.

As soon as the tube is disposed in the horizontal

position shown in Fig. 2, the manipulating tool (not shown) may be disengaged from the pull ring 23 and engaged with the plate 37, in a manner not shown, for the purpose of lifting the tube and sleeve from the hinge arms 8.

Attention is directed to the fact that the collar 27 on the lower end of the tube 20 is provided with a lug 40 which extends into a notch 41 in the lower end of the sleeve 25 and serves to require proper alignment of the pull ring 23 and sleeve. The lug 40 in cooperation with the slot 41 prevents relative rotation between the tube 20 and sleeve 25 when force is exerted on the pull ring to move the tube to circuit-closing position.

The collar 27 is also provided with a pair of spaced laterally extending lugs 44 between which the spring strip 29 is positioned when held to the tube by the fuse link 33. The lugs 44 serve to prevent the fuse link from being accidentally displaced sidewise relative to the lower end of the strip 29 and also assist the lug 40, to some degree, in holding the tube 20 non-rotatively relative to the sleeve 25.

After dismounting of the cartridge from the arm 5, the damaged link 33 may be removed from the tube 20 in an obvious manner, and a new link placed therein by passing it through the upper end of the tube and about the lower end thereof and secured to the sleeve 25 as described, after the tube and sleeve are properly aligned and the curved end 32 of the spring strip 29 is disposed beneath the collar 27.

When a new fuse link has been placed in the fuse tube, the fuse may be mounted on the pivot arms 8 by means of a manipulating stick (not shown) in engagement with the plate 37. Fig. 4 illustrates the position the tube first assumes after mounting upon arms 8. In this position, the lugs 36 upon the sleeve 25 contact with the projecting fingers 38 on the arms 8 and cooperate with the trunnions 35 to hold the tube as shown. The fingers 38 are inclined downwardly so that the tube will remain with its trunnions engaging the hooked arms 8 while in the position illustrated in Fig. 4. The fuse may be moved from the position shown in Fig. 4 to that shown in Fig. 1 by means of a manipulating stick in engagement with the pull ring 23. As the cap 24 moves to the circuit-closing position, it will engage the portion 17 of the contact plate 13 and urge the plate and spring strip 18 upwardly until it passes the retainer portion 16.

While I have described the operation of the device under the urge of the coil spring 26, it is obvious that it will move to open a circuit without the spring for the reason that the angle at which the fuse is disposed will permit it to freely slide in the sleeve 25 and for the further reason that the contact spring plate 13 biases the tube toward sliding movement.

If it is desired to open the circuit under normal conditions and without destroying the link 33, it is only necessary to pull the fuse by means of the pull ring 23 in a clockwise direction relative to Fig. 1 about the trunnions 35 and to dispose the fuse in the position shown in Fig. 4 with the lugs 36 resting upon the fingers 38.

An arcing gap may be provided comprising a current conducting rod 45 secured in any suitable manner (not shown) to the transformer casing 1 and a second current conducting rod 46 in spaced relation to and above the rod 45 and secured to and in electrical contact with the contact plate 13.

One of the advantages of disposing the tube 21 at an angle, relative to the casing 1, is in projecting metallic vapors, produced when the fuse link ruptures, outwardly away from the casing 5 and also in supporting the tube in spaced relation to the casing after it has moved to open-circuit position. As a result, a comparatively compact fuse mounting and structure are provided for mounting on a transformer casing in a 10 position which is readily accessible for re-fusing and insertion into circuit-closing position.

From the foregoing it becomes apparent that a dropout fuse structure has been provided which comprises a novel combination securing all of the 15 objects of this invention and embodying a comparatively simple structure, which may be manufactured at a minimum cost, may be easily installed and manipulated, and is efficient in operation.

20 I claim:

1. In combination with a transformer casing having a lead-in surrounded by an insulating bushing, a pivot arm secured to the lead-in, said arm being mounted on and extending laterally 25 from said bushing, an insulating block secured to the arm directly above said bushing, a terminal member secured to and extending from the block, said arm and member being disposed in a vertical plane common to both and to the axis of 30 said bushing, and an expulsion fuse cartridge pivotally supported on said arm and electrically connecting said arm and terminal, said cartridge being inclined upwardly from its pivotal support on said arm toward the axis of said bushing and 35 downwardly away from said casing, whereby the path of gases expelled from said cartridge will be away from said casing.

2. In combination with a transformer casing having a lead-in surrounded by an insulating bushing, a pivot arm secured to and extending laterally from said lead-in and bushing, an insulating block secured to said arm directly above 40 said bushing, a terminal member secured to and extending from said block, said arm and member being disposed in a vertical plane common to both and to the axis of said bushing, an expulsion fuse cartridge electrically connecting said arm and terminal, and a sleeve 45 slidable on the cartridge and pivotally mounted on said arm, said cartridge being biased for sliding movement in said sleeve and being inclined upwardly from the pivotal support of said sleeve toward the axis of 50 said bushing and downwardly away from said casing, whereby the path of gases expelled from said cartridge will be away from said casing.

55 3. In combination with an insulating support having spaced hooked pivot bearings each provided with a stop finger extending horizontally and downwardly from its corresponding bearing 60 and having a terminal above said bearings, a fuse cartridge comprising an expulsion fuse tube provided at one end with a contact engaging said terminal and at the other end with a sleeve having a pair of trunnions mounted in said bearings 65 and a pair of lugs spaced above said trunnions for contact with said fingers, whereby to support said tube in a horizontal position when in open-circuit position.

4. In combination with an insulating support 70 having a supporting member terminating in spaced hooked pivot bearings each provided with a stop finger extending horizontally and downwardly from its corresponding bearing and having a terminal above said bearings, of a fuse cartridge comprising an expulsion fuse tube pro-

vided at one end with a contact engaging said terminal and at the other end with a sleeve having a pair of trunnions mounted in said bearings and a pair of lugs spaced above said trunnions for contact with said fingers when said tube is 5 in open-circuit position, and contact means carried by said supporting member and extending directly above said lugs when said tube is in circuit-closing position.

5. In combination with an insulating support 10 having a supporting member terminating in spaced hooked pivot bearings and having a terminal above said bearings, a fuse cartridge comprising an expulsion fuse tube provided at one end with a contact engaging said terminal and 15 at the other end with a sleeve having a pair of trunnions mounted in said bearings and a lug on said sleeve spaced above said trunnions, and contact means carried by said supporting member and extending directly above said lug when 20 said tube is in circuit-closing position, said lug being engageable with said contact means to hold said sleeve in said bearings when said tube is in circuit-closing position.

6. In combination with an insulating support 25 having a supporting member terminating in spaced hooked pivot bearings and having a terminal above said bearings, a fuse cartridge comprising an expulsion fuse tube provided at one end with a contact engaging said terminal and 30 at the other end with a sleeve slidable on the tube and having a pair of trunnions mounted in said bearings and a lug on said sleeve spaced above said trunnions, said tube being biased for 35 sliding movement in said sleeve, contact means carried by said supporting member and extending directly above said lug when said tube is in circuit-closing position, said lug being engageable with said contact to hold said sleeve in said bearing when said tube is in circuit-closing position, and a fuse link in said tube electrically connecting said contact and sleeve and normally restraining said tube against sliding movement. 40

7. In combination with an insulating support 45 having a supporting member terminating in spaced hooked pivot bearings and having a terminal above said bearings, a fuse cartridge comprising an expulsion fuse tube provided at one end with a contact engaging said terminal and at the other end with a sleeve slidable on the tube and having a pair of trunnions mounted in said bearings and a lug on said sleeve spaced above said trunnions, said tube being biased for 50 sliding movement in said sleeve, contact means carried by said supporting member and extending directly above said lug when said tube is in circuit-closing position, said lug being engageable with said contact to hold said sleeve in said bearing when said tube is in circuit-closing position, and a fuse link in said tube electrically connecting said contact and sleeve and normally restraining said tube against sliding movement, said contact means being in frictional engagement with said sleeve, thereby to hold said tube against 55 pivotal movement in said bearings when moving to and disposed in open-circuit position.

8. In combination with an insulating support 60 having a supporting member terminating in spaced hooked pivot bearings and having a terminal above said bearings, a fuse cartridge comprising an expulsion fuse tube provided at one end with a contact engaging said terminal and at the other end with a sleeve slidable on the tube and having a pair of trunnions mounted in said 65 bearings, said tube being biased for sliding move- 70

75

- ment in said sleeve, contact means carried by said supporting member, and a fuse link in said tube electrically connecting said contact and sleeve and normally restraining said tube against sliding movement, said contact means being in frictional engagement with said sleeve, thereby to hold said tube against pivotal movement in said bearings when moving to and disposed in open-circuit position.
10. In combination with an insulating support having a supporting member terminating in spaced hooked pivot bearings and having a terminal above said bearings, a fuse cartridge comprising an expulsion fuse tube provided at one end 15 with a contact engaging said terminal and at the other end with a sleeve slidable on the tube and having a pair of trunnions mounted in said bearings and a lug spaced above said trunnions, said tube being biased for sliding movement in said sleeve and being inclined upwardly from a horizontal plane extending through said trunnions and forwardly toward said support, contact means carried by said supporting member and extending directly above said lug when said tube 20 is in circuit-closing position, and a fuse link in said tube electrically connecting said contact and sleeve and normally restraining said tube against sliding movement, said contact means being in frictional engagement with said sleeve, thereby to hold said tube against pivotal movement in said bearings when moving to and disposed in open-circuit position.
10. In combination with an insulating support having a supporting member terminating in spaced hooked pivot bearings and having a terminal above said bearings, a fuse cartridge comprising an expulsion fuse tube provided at one end with a contact engaging said terminal and at the other end with a sleeve slidable on the tube and having a pair of trunnions mounted in said bearings, said tube being biased for sliding movement in said sleeve and being inclined upwardly from a horizontal plane extending through said trunnions and forwardly toward said support, contact means carried by said supporting member, and a fuse link in said tube electrically connecting said contact and sleeve and normally restraining said tube against sliding movement, said contact means being in frictional engagement with said sleeve, thereby to hold said tube against pivotal movement in said bearings when moving to and disposed in open-circuit position.
11. In a drop-out fuse structure, the combination with an insulating support having a pivot arm and a terminal spaced therefrom, of a fuse cartridge comprising a tube having a contact at one end engaging said terminal, a collar secured to the other end of said tube, a sleeve slidable on said tube between said contact and collar, said sleeve being pivotally supported on said arm, a flip-out spring strip secured to said sleeve and having an integral portion bent to be positioned beneath said collar, and a fuse link in said tube connecting said contact and sleeve and normally holding said spring strip portion beneath said collar, said tube being biased for sliding movement in said sleeve and normally restrained against said movement by said spring strip.
12. In a drop-out fuse, the combination with an insulating support having spaced relatively insulated current conducting members, of a fuse structure comprising a tube having a closure contact at one end and a sleeve on said tube at the other end thereof slidably supporting said tube 70 and a fuse link connecting said contact and sleeve and normally holding said tube against sliding movement, said sleeve being pivotally mounted on one of said members and said contact normally engaged with the other of said members, said tube being disposed at an angle relative to a vertical plane paralleling the pivotal mounting of said sleeve when in circuit-closing position and being slidable in a path coincident with said angle, and means on said support holding said sleeve against pivotal movement while said tube is sliding in said sleeve and when said tube has moved to open-circuit position.
13. In a drop-out fuse, the combination with an insulating support having spaced relatively insulated current conducting members, of a fuse electrically connecting said members and slidably and pivotally mounted on one of said members, said fuse being disposed angularly relative to a vertical plane paralleling the pivotal mounting of said fuse when in circuit-closing position, means holding said fuse against pivotal movement during sliding movement and when in open-circuit position, and current responsive means normally holding said fuse against sliding movement.
14. In combination with a transformer casing having a lead-in conductor surrounded by an insulating bushing, of a supporting arm mounted on said bushing and secured to said conductor, said arm extending laterally of said bushing and having a pivot bearing, an insulating block secured to said support and extending above said bearing, a resilient line terminal secured to said block remote from said support, a fuse connecting said support and terminal, said fuse being pivotally mounted in said bearing and slidable in a path extending away from said casing, and means holding said fuse against pivotal movement while sliding in and subsequent to sliding in said path.
15. In a drop-out fuse of the class described, a support having a pivot bearing, a sleeve pivoted in said bearing, a tube slidable in said sleeve, a U-shaped contact frictionally embracing said sleeve, and a lug on said sleeve between said bearing and said contact engageable with said contact to hold said sleeve in said bearing when said tube is in circuit-closing position.
16. In a drop-out fuse of the class described, a support having a pivot bearing, a sleeve pivoted in said bearing, a tube slidable in said sleeve, a collar secured to said tube, a coil spring in said tube reacting between said sleeve and collar, a fuse link in said tube normally holding said tube against sliding motion, a contact frictionally embracing a portion of said sleeve, and a lug on said sleeve between said pivot bearing and contact engageable with said contact to hold said sleeve in said bearing when said tube is in circuit-closing position.
17. In a drop-out fuse of the class described, a support having an arm provided with a hook bearing, a sleeve having a trunnion mounted in said bearing, a tube carried by said sleeve, a contact member carried by said arm, and a lug on said sleeve between said bearing and said member and engageable with said member to hold said trunnion in said bearing.
18. In a drop-out fuse of the class described, a support having an arm provided with a hook bearing intermediate its ends, a sleeve having a trunnion mounted in said bearing, a tube carried by said sleeve, a contact member carried by said arm, and a lug on said sleeve between said bearing and said member and engageable with said member to hold said trunnion in said bearing, said lug being engageable with an end of said tube.

- arm for supporting said tube in open-circuit position.
19. In a drop-out fuse, the combination with a sleeve, of a tube slidable in said sleeve, a collar secured to said tube, a latching spring on said sleeve and engageable with said collar to hold said tube against sliding movement, and a fuse link in said tube normally holding said spring in engagement with said collar, said fuse link overlying said spring and said collar having means for holding said link against displacement relative to said spring.
20. In a drop-out fuse, the combination with a sleeve, of a tube slidable in said sleeve, a collar secured to said tube, a latching spring on said sleeve and engageable with said collar to hold said tube against sliding movement, a fuse link in said tube normally holding said spring in engagement with said collar, said fuse link overlying said spring and said collar having means for holding said link against displacement relative to said spring, and means coacting between said collar and sleeve for aligning said tube and sleeve rotatively.
21. In a drop-out fuse, the combination with a sleeve, of a tube slidable in said sleeve, a collar secured to said tube, a coil spring in said sleeve and disposed about said tube, a latching spring on said sleeve engageable with said collar to hold said coil spring under compression and said tube against sliding motion, and a fuse link in said tube normally holding said latch spring in engagement with said collar, said link overlying said latch spring and said collar having means for holding said link against displacement relative to said spring.
22. In a drop-out fuse, the combination with a sleeve, of a tube slidable in said sleeve, a collar secured to said tube, a coil spring in said sleeve and disposed about said tube, a latching spring on said sleeve engageable with said collar to hold said coil spring under compression and said tube against sliding motion, a fuse link in said tube normally holding said latch spring in engagement with said collar, said link overlying said latch spring and said collar having means for holding said link against displacement relative to said spring, and means coacting between said collar and sleeve for aligning said tube and sleeve rotatively.
23. In a drop-out fuse, the combination with an insulating support having a pivot bearing, of a sleeve pivotally mounted in said bearing, a tube slidable in said sleeve, resilient means co-acting between said tube and sleeve to cause relative sliding movement, a latch spring on said sleeve

for holding said tube against sliding motion, a fuse link in said tube holding said spring in engagement with said tube, a contact on said support frictionally engaging said sleeve, and a lug on said sleeve between said bearing and contact and engageable with said contact to hold said sleeve on said bearing.

24. In a drop-out fuse, the combination with an insulating support having a pivot bearing, of a sleeve pivotally mounted in said bearing, a tube 10 slidable in said sleeve, resilient means co-acting between said tube and sleeve to cause relative sliding movement, a latch spring on said sleeve for holding said tube against sliding motion, a fuse link in said tube holding said spring in 15 engagement with said tube, a contact on said support frictionally engaging said sleeve, a lug on said sleeve between said bearing and contact and engageable with said contact to hold said sleeve on said bearing, and means carried by said tube and coacting with said sleeve to hold said tube non-rotatively in said sleeve.

25. In a drop-out fuse, the combination with an insulating support having a pivot bearing, of a sleeve pivotally mounted in said bearing, a tube 25 slidable in said sleeve, resilient means co-acting between said tube and sleeve to cause relative sliding movement, a latch spring on said sleeve for holding said tube against sliding motion, a fuse link in said tube holding said spring in engagement with said tube, a contact on said support frictionally engaging said sleeve, a lug on said sleeve between said bearing and contact and engageable with said contact to hold said sleeve on said bearing, said link overlying said latch spring, 30 and means carried by said tube for preventing displacement of said link relative to said spring.

26. In a drop-out fuse, the combination with an insulating support having a pivot bearing, of a sleeve pivotally mounted in said bearing, a tube 40 slidable in said sleeve, resilient means co-acting between said tube and sleeve to cause relative sliding movement, a latch spring on said sleeve for holding said tube against sliding motion, a fuse link in said tube holding said spring in 45 engagement with said tube, a contact on said support frictionally engaging said sleeve, a lug on said sleeve between said bearing and contact and engageable with said contact to hold said sleeve on said bearing, said link overlying said latch spring, and means carried by said tube for preventing displacement of said link relative to said spring, said means including a portion coacting with said sleeve to hold said tube non-rotatively in said sleeve.

55 WILLIAM O. SCHULTZ.
